WILLIAM M. WATTIE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

THREAD-CONTROLLING DEVICE FOR LOOM MAGAZINES

Application filed July 3, 1929. Serial No. 375,718.

This invention relates to improvements in devices for keeping taut the weft ends which extend from reserve bobbins in a weft replenishing mechanism and it is the general 5 object of the invention to provide a simple weft clearing device for the apparatus which acts to tighten the threads.

In my co-pending application Ser. No. 347,087 I have shown a travelling friction 10 surface to engage and tighten the weft ends of reserve bobbins. I find that the weft ends accumulate on the surface sufficiently to interfere with efficient operation. It is a further object of my present invention to provide 15 clearing means which will remove the weft ends from the friction surface.

It is a further object of my present invention to connect the friction surface actuating mechanism with the clearing device so 20 that any adjustment made in the mechanism will cause a corresponding adjustment in the clearer. In this connection it is a still further object of my invention to provide a clearer mounted so as to be movable toward 25 and from the travelling surface for purposes of adjustment but in normal operation actuated to sweep across the width of the belt to accomplish the result previously mentioned.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a front elevation of one end of a lay and magazine having my invention applied thereto,

Fig. 2 is a detailed horizontal section on line 2—2 of Fig. 1, and

Fig. 3 is a vertical section on line 3—3 of Fig. 1.

Referring to Fig. 1 I have shown the magazine M in which is mounted a stack of reserve bobbins B from which extend the weft ends W. The lay L is mounted for reciprocating movement back and forth under the 50 magazine and is of the usual construction.

From the magazine M extends a rod 10 having secured thereto a holder 11 the lower part of which supports a stud 12 affording pivotal support for an actuating lever 13. The latter has a shoe 14 to engage a cam 15 secured to and moving with the lay. A pawl 16 on the upper end of the lever engages a ratchet 17 to move the same in a clockwise direction as viewed in Fig. 1. A torsion spring 18 having one end 19 extending into the stand and the other end 20 bearing against the lower arm of the lever 13 acts to hold the latter against the cam 15 and is the means by which the ratchet is rotated.

A stud 21 carried by the lower part of the holder has adjustably mounted thereon for angular movement an arm 22 on which is pivotally mounted for free rotation a roll 23. The arm may be moved to any angular position with respect to the holder so as to vary the distance between the centers of the ratchet wheel 17 and the roll 23. An endless belt 24 passes over the roll 23 and also a second roll 25 secured to and moving with the ratchet wheel. The belt is provided with a surface having a sufficient frictional engagement with the weft ends W to hold the latter taut.

In operation of the mechanism thus far described the lay advances to give lever 13 a counter-clockwise movement against the action of spring 18, causing the pawl to move over a tooth on the ratchet. As the lay recedes the spring will act to hold the shoe 14 against the cam 15 and will also move the pawl 16 to the right as viewed in Fig. 1, thereby causing a partial rotation of the ratchet wheel 17 and the upper cylinder 25. The arm 22 is set so that the belt is sufficiently tight to be moved by rotation of the roll 25 and it is in this way that the weft ends which are laid across the belt 24 are held taut. The matter thus far described is substantially the same as that set forth in the aforesaid application and forms no part of my present invention.

The cam 15 is formed as part of a casting 30 secured to the lay by means of bolts 31. In my present invention I extend one end of the member 30 to provide a finger 32 which

is split as at 33 and provided with a screw 34 the effect of which is to draw the split parts of the finger together. Between the split portions of said finger I extend the shank 35 of a brush or other similar device 36. The shank extends in a direction generally transverse to the belt so that by adjustment of the finger longitudinally of the shank the bristles of the brush may be moved 10 toward or from the belt, as will be clearly apparent from Fig. 1.

During the operation of my improvements the bristles or brush will move with the lay in a back and forth direction over the surface of the belt to engage any weft end which may be held frictionally to the belt to remove the same. Should the belt become slack the arm 22 may be moved to the right and a corresponding adjustment made with respect to 15 the shank 35 to insure proper engagement between the bristles and the belt. In this connection it should be understood that the studs 12 and 21 and also the lower roll 23 extend in a direction which is substantially 20 parallel to the back and forth movement of the lay so that the brush 36 is in substantial contact with the belt for the full width thereof.

From the foregoing it will be seen that I 30 have provided a very simple form of clearing device which moves with the lay across that part of the belt to which weft ends may cling, but it will be seen that the brush is placed so as to permit a considerable length 35 of weft to engage the belt before arriving at a position where they can be engaged by the brush. It will further be seen that the device which supports the actuator for the lever 13 also supports the brush or bristles. Furthermore, any movement on the part of the arm 22 40 which is made necessary to provide proper tautness for the belt can be accompanied by longitudinal adjustment of the shank 35 relatively to the finger 32.

Having thus described my invention it will 45 be seen that changes and modifications may be made therein by those skilled in the art without departing from the spirit and scope of the invention and I do not wish to be limited to the details herein disclosed, but what 50 I claim is:

1. In a weft end tensioning device including a travelling surface movable in a given path and adapted to engage the weft ends, 55 a lay, movable in a direction transverse to the movement of the surface, and a clearer on the lay to engage the surface and remove weft ends therefrom.

2. In a weft end tensioning device including a travelling surface movable in a given path and adapted to engage the weft ends, a 60 lay, movable in a direction transverse to the movement of the surface, and a clearer on the lay to engage the surface and remove weft ends therefrom, said clearer including a

brush with flexible bristles to engage the surface.

3. In a weft end tensioning device including a travelling surface movable in a given path and adapted to engage the weft ends, a 70 lay movable in a direction transverse to the movement of the surface, a normally fixed support for the surface movable to assume a plurality of positions relatively to the length of the lay, and a clearer carried by the lay 75 to engage the surface and remove weft ends therefrom, the clearer being movable relatively to the lay in the direction of the length thereof to engage the surface in each of its several possible positions.

4. In a weft end tensioning device including a travelling surface movable in a given path and adapted to engage the weft ends, a lay movable in a direction transverse to the movement of the surface, means including an 80 element on the lay to actuate the travelling surface, a clearer to engage the surface to remove weft ends therefrom, and a common support for the element and clearer mounted on the lay.

5. In a weft end tensioning device for a magazine loom having a lay moving back and forth therein, a weft end engaging surface, means to move said surface intermittently to exert a frictional strain on the weft 90 ends in contact therewith, and a clearer carried by the lay and movable across the surface and in a direction transverse to the movement of the surface to engage the weft ends and remove the same from the surface.

6. In a weft end tensioning device for a loom, a weft end engaging surface, means to move said surface to exert a frictional strain on the weft ends in contact therewith, and a clearer movable across the surface and in a 105 direction transverse to the movement of the surface to engage the weft ends and remove the same from the surface.

7. In a weft end tensioning device for a loom, a weft end engaging surface, means to move said surface intermittently to exert a frictional strain on the weft ends in contact therewith, and a clearer movable across the surface and in a direction transverse to the movement of the surface to engage the weft 110 ends and remove the same from the surface, said clearer being movable relatively to the surface when the latter is moving to exert frictional strain on the weft.

8. In a weft tensioning device for a loom, 120 a friction surface to engage the weft ends to tension the same, a clearing device for the surface to remove weft ends clinging thereto, and means to cause simultaneous movement of the surface in one direction and the clearer 125 in a direction transverse thereto.

9. In a weft tensioning device for a loom having a lay moving back and forth therein, a friction surface to engage the weft ends to tension the same, a clearing device for the 130

surface to remove weft ends clinging thereto, and means operated by the lay to cause simultaneous movement of the surface in one direction and the clearer in a direction transverse thereto.

5 In testimony whereof I have hereunto affixed my signature.

WILLIAM M. WATTIE.
